UNITED STATES PATENT OFFICE.

ERNEST A. WOELFEL, OF PEABODY, MASSACHUSETTS.

DESIGN FOR LEATHER.

Application filed August 2, 1922. Serial No. 3,271. Term of patent 3½ years.

To all whom it may concern:

Be it known that I, ERNEST A. WOELFEL, a citizen of the United States, residing at Peabody, in the county of Essex and State of Massachusetts, have invented a new, original, and ornamental Design for Leather, of which the following is a specification, reference being had to the accompanying drawing, forming part thereof.

The figure is a plan view of a piece of leather, showing my new design.

I claim:

The ornamental design for leather, as shown.

ERNEST A. WOELFEL.
